PENCIL COMPASS

Alex Augustin, Sparrowbush, N.Y., assignor to A. & W. Products Co., Inc., Port Jervis, N.Y., a corporation of New York
 Original application Feb. 17, 1960, Ser. No. 9,243. Divided and this application Aug. 1, 1961, Ser. No. 128,505

1 Claim. (Cl. 33—27)

The present invention relates generally to compasses and specifically to an improved pencil clamp for use in conjunction with a pencil compass.

This application is a division of my earlier filed application, Serial No. 9,243, filed February 17, 1960 and entitled Compass Pencil Clamp.

The use of a compass to draw a circle or a portion of an arc is well known in the art and a large variety of differing compasses have been produced. The present invention is concerned specifically with that type of compass which employs the use of a pencil to describe the arc or circle produced. The pencil compass is a relatively inexpensive item and is generally designed for mass production manufacture and low selling price. A persistent problem which has existed in the manufacture of pencil compasses has been the difficulty in producing a mechanism which will easily and accurately clamp a pencil within the compass and at the same time, be relatively inexpensive to manufacture. Included within the disadvantages of the prior art clamps for pencil compasses has been the general failure to solve the problem connected with the requirement for easy removal of the pencil for sharpening, the accurate adjustment of the pencil relative to the compass as the pencil point becomes worn and a clamping of a pencil within the pencil compass without damaging the pencil.

Generally, it is an object of the present invention to provide a pencil clamp for use in a pencil compass which eliminates the disadvantages of the prior art pencil clamps as described above. Specifically it is an object of the present invention to provide a pencil clamp which will firmly secure a pencil to one leg of a compass and which will allow for easy positioning of the pencil.

A further object of the present invention is to provide a pencil clamp which will not mar the surface of a pencil contained therein.

It is still a further object of the present invention to provide a pencil clamp which is relatively easy to manufacture in mass production techniques and which effectively clamps a pencil such that its position within the clamp may be adjusted.

In accordance with one illustrative embodiment of the present invention there is provided a conventional pencil compass which incorporates, as an integral part of one of its legs, an improved pencil clamp. The pencil clamp comprises a cylindrical band having a longitudinal slit therein and including two integrally formed ears on opposite sides of said longitudinal slit. Releasable clamping means are provided and includes a slide having converging camming walls which are provided about the protruding ears such that relative movement between the slide and the ears is effective to draw the ears together. This action is effective to decrease the internal diameter of the cylindrical band and, thereby, clamp a pencil within the clamp.

The above brief description as well as further objects, features and advantages of the present invention will be best appreciated by reference to the following detailed description of a presently preferred embodiment, when taken in conjunction with the accompanying drawings wherein:

FIG. 1 is a side elevational view of a pencil compass

2

incorporating a pencil holder according to the present invention;

FIG. 2 is an enlarged fragmentary view of the pencil clamp shown in FIG. 1, the clamp being illustrated in its clamping position;

FIG. 3 is a view similar to FIG. 2 with the clamp being illustrated in its opened position; and,

FIG. 4 is a sectional view taken along the lines 4—4 of FIG. 2 and looking in the direction of the arrows.

- 10 Referring now specifically to the drawings, there is shown in FIG. 1 a pencil compass, generally labelled by the numeral 100, incorporating a pencil holder or clamp generally designated by the numeral 112. The pencil compass 100 is of conventional structure and is comprised of two legs 114 and 116, which are pivotally joined at their upper ends by the pivot rivet 118. Frictional clamping forces are provided between the two legs 114, 116 by the pivot rivet 118, spring washers 120, and the center plate 122 which has a center post 124. The pivot rivet 118, the spring washer 120, the center plate 122 and the legs 114, 116 are assembled in a manner which is well known to those skilled in the art, such that the center post 124 always bisects the angle between the legs 114, 116. The leg 114 has attached to its lower portion a 15 pointed member 126 about which the compass 110 is pivoted when in use. The other leg 116 has an arcuate extension 128 which extends inwardly towards the leg 114 and extends beyond the leg 114. The arcuate extension 128 serves as an index of the radius of the arc described by the compass. A scale 130, inscribed on the extension 128 coats with the index marker 132 on the leg 114 to provide this reading. In use, the operator of the pencil compass 100 places the pointed member 126 at the center of an arc to be formed and with the pencil P which is supported in the holder 112 and he describes an arc about the point of member 126.

40 The pencil holder, best seen in FIGS. 3 and 4, consists of a cylindrical band 134 which has an internal diameter approximately equal to the diameter of the pencil P. The band 134 has an opening or slit 136 which runs the length of the band 134 and has two juxtaposed side edges 138, 140 which define the width of the opening 136. The cylindrical band 134 is constructed of a flexible material, such that the width of the slit 136 may be elastically varied. It will be appreciated that upon a decrease of the width of the slit 136 by a movement of the side edges 138, 140 towards each other, the internal diameter of the cylindrical band 134 will be decreased thereby positively gripping a pencil P disposed therein.

45 Clamping mechanisms 142 are provided to accomplish this result. The clamping mechanisms 142 consist of a pair of ears 144, 146 which extend outwardly from the cylindrical band 134 at opposing points along the edges 50 138, 140 respectively of the opening 136. The ears 144, 146 are bent away from the opening 136 and are folded partially back against the cylindrical band 134. A slide 148 is provided with converging camming walls 152, 154 which define an opening 150 contained therein. As may 55 be seen in FIGS. 2 and 3, the converging camming walls 152, 154 are closer together at the upper end of the slide 148 than at the lower end thereof. The clamping ears 144, 146 are contained within the opening 150 and are engaged in abutting relationship with the respective camming walls 152, 154. It will thus be appreciated that 60 when the slide 148 is moved downwardly relatively to the ears 144, 146 the opening 136 will be narrowed by the camming action of the camming walls 152, 154 on the ears 144, 146 respectively, and thus, the internal diameter of the cylindrical band 134 will be reduced into a 65 clamping position. The clamp 112 is pictured in its clamping position in FIG. 2. A finger tab 156 is pro- 70

FIG. 1 is a side elevational view of a pencil compass

vided on the upper end of the slide 148 to facilitate the movement of the slide 148 relative to the ears 144, 146. When the slide 148 is moved from the position shown in FIG. 2 to the position shown in FIG. 3, i.e., moved upwardly relative to the ears 144, 146, the ears 144, 146 will be engaged in the lower portion of the slide 148 wherein the camming walls 152, 154 are spaced relatively far from each other. Thus, the clamping ears 144, 146 will be allowed to spread apart and thus increase the diameter of the cylindrical band 134. When a pencil P has been placed in the desired position relative to the holder or clamp 112 as seen in FIG. 3, the operator moves the slide 148 by means of the finger tab 156 downwardly relative to the ears 144, 146 thus camming them towards each other by the action of the camming walls 152, 154.

It will be appreciated that the present invention provides easily operative and effective clamping means to retain a pencil within a pencil compass. A simple camming device is utilized to decrease the width of an opening in a cylindrical band, the cylindrical band being approximately the diameter of a pencil. When the sides of the opening are drawn together, the pencil is clamped within the cylindrical band. Positioning of the pencil with respect to the band is relatively simple and the device itself is both dependable and relatively inexpensive to manufacture.

A latitude of modification, substitution and change is intended in the foregoing disclosure and in some instances some features of the invention will be used without a use of other corresponding features. Accordingly, the claims herein should be construed broadly and in a manner consistent with the spirit and scope of the invention.

What I claim is:

A pencil holder for use with a two legged pencil com- 35

pass comprising a stamped one piece resilient cylindrical band integrally formed with one of the legs of said pencil compass, said cylindrical band having a longitudinal slit formed therein having spaced parallel edges extending the length of said band, said band being resiliently deformable between a normal position wherein the diameter of the band is slightly larger than the diameter of a pencil to be held within said band and a clamping position wherein the parallel edges of said slit are drawn together and the diameter of said band is reduced, a pair of ears extending outwardly from said band at points at substantially the middle of said parallel edges, said ears being integral extensions of the material of said band and said leg, and releasable clamping means comprising a slide plate having a central cut-out having a pair of converging camming edges on opposite sides of said cut-out, said slide plate being in cooperating engagement with said ears with said ears extending through said cut-out and engaged against said converging camming edges, said slide plate being movable longitudinally through a prescribed stroke for moving said camming edges with respect to said ears to draw said ears together and thereby to resiliently deform said band into said clamping position at one end of the stroke and to release said ears for movement away from each other to allow said band to assume its normal, non-clamping position, said ears being substantially smaller in the longitudinal direction than said slide plate to allow said slide plate to be moved through said longitudinal stroke.
